GRINDING, LAPPING, OR POLISHING MACHINE FOR DIAMONDS OR OTHER CRYSTALS AND THE LIKE

Frederick Charles Jearum, Sutton, England

Application April 6, 1943, Serial No. 482,008
In Great Britain May 16, 1942

9 Claims. (Cl. 51—229)

This invention relates to machines for grinding or lapping or polishing (hereinafter referred to as lapping) diamonds or other crystals or minerals (hereinafter referred to as stones) for industrial purposes or for the jewellery trade, upon a lap or revolving cutting disc or scaife (hereinafter called a scaife) and the invention has for its object the lapping of stones to provide perfectly flat faces or tables thereon and to provide exactly parallel and flat faces on the opposite sides of the stones (such as for example for producing parallel facets on opposite sides of a stone for making a diamond or like die), and includes the provision of means to facilitate ready inspection from time to time of the lapping operation and convenient interchange of dops.

A further aim of the invention is to provide means adapted automatically to find the cutting grain of a diamond or other stone having a particular cutting grain without the skilled inspection and setting of the stone usually required for the purpose of finding the grinding position.

The invention consists in a machine of the type indicated having a tang, the axis of which is fixed in a horizontal plane, and a head on the end of the tang adjacent the scaife comprising: a vertical slideway, a slider freely displaceable vertically on said slideway under or against gravity action, a dop or stone mount having a barrel or body provided with a coaxial rotatable member carrying stone holding means, a vertical bed on said slider open to receive said barrel and shaped to locate said barrel laterally with the axis of the rotatable member vertical, complementary interengaging means on the barrel and bed for locating the barrel longitudinally of the bed and releasable clamping means for securing said interengaging means, the arrangement being such that when seated on the bed the barrel and rotatable member are confined to the vertical displacements of the slider.

Further features of the invention will be hereinafter described and defined in the claims.

In the accompanying drawing—

Fig. 1 is a side elevation partly in section of a machine constructed according to one form of the invention;

Fig. 2 is a plan view of the machine according to Fig. 1; while

Fig. 3 is a rear end elevation of the machine.

In carrying the invention into effect according to one convenient mode as described by way of example, a horizontal bed 1 having bevelled edges 1a and a longitudinal slot 1b of inverted T shape in cross-section is provided as a mount for a de-

5 tachable slideway block 2 for a tang or arbor 3. The block on its underside has marginal bevelled flanges to fit the bevels 1a of the bed and is adapted to be releasably coupled to the bed by means of a T-headed member 2a (fitting in the longitudinal groove of the bed) carried by a sheave engaged with an eccentric 2b mounted on a horizontally rotatable pin 2c having an operating handle 2d at the side of the block. The block is provided with 10 a slideway 2e of diamond or square shape in cross-section, a diagonal of the square or diamond being positioned in the vertical plane. The slideway may be horizontally divided and formed in two halves connected together by bolts or set screws and a set screw 2f is provided in the upper half of the slideway for locking the tang in any adjusted position.

The tang 3 comprises a horizontal bar of corresponding cross-section to the slideway into 20 which it fits and has at its forward and rear ends on its underside anchorages 3a, 3b (the anchorage 3b of which may be adjustable for tension by manipulation of the nut 3c) for a wire or ribbon 3d which is lapped around a drum on a transverse spindle 3e mounted in horizontal bearings 25 in the slideway block. The spindle has a milled head 3f or other manipulating head for rotating the drum, for winding the tang to and fro longitudinally in the slideway. At the forward extremity of the tang a head 4 is provided in which is formed a vertical geometric slideway 4a having vertical sets of ball bearings 4b adapted to receive a tool bed slide member 5.

The bed of the member 5 is in plan of V shape 35 or has a double bevelled channel (as seen at 5a, Fig. 2) for receiving and seating the cylindrical barrel 6 of a mechanical dop or like tool mount for the stones to be treated. The mechanical dops for use in the apparatus may be interchangeable and each have a horizontal lug 6a fixed to the barrel and adapted to extend into a cavity at the base of the bevelled or V-shaped bed. The lug has a vertical bore into which is fitted the eccentric portion 7 of a vertically rotatable pin 1a insertable in a bore 5c in the bed 5, the arrangement being such that when the pin is inserted and rotated in the lug bore the eccentric clamps the barrel of the dop upon the bed.

The barrel is formed to serve as a mount for a 40 vertical sleeve 8. The sleeve is carried in double bevelled bearings and has upper and lower conical shoulder members 8a for engaging the bevels. The lower shoulder is in one with or fixed on the sleeve while the upper shoulder is slideable on a key 8c fitted in a keyway located in a thread-

ed portion $8b$ at the upper end of the sleeve. When it is required to use the dop with the stone in a fixed position or when it is required to rotate it from time to time and then fix it in the reset positions, a milled clamping nut $8d$ is screwed down directly on to the upper conical member $8a$. When, however, it is desired to provide means on the dop for giving it a slow, continuous rotation about the vertical axis, a worm wheel 9 is keyed upon the thread $8b$ between the nut $8d$ and the upper conical member $8a$. Brackets 10 support a worm $10a$ with which a flexible drive shaft $10b$ is coupled.

This revolution of the stone constantly turns the cutting grain of the stone about the vertical axis so that the grain is automatically exposed at least twice in each revolution to the flow of the abrasive grains carried by the scaife.

At the lower end the sleeve carries a head 11 in which is mounted a pair of pivoted stone gripping levers or fingers $11a$ operated by slide blocks in engagement with right- and left-hand screw threads (not shown) of an actuating member having a milled manipulating head $11b$. The gripping fingers are adapted to engage a stone upon either side, the stone being positioned vertically upon a flat base support in the form of a short spindle $12a$ mounted in the bore of the sleeve and adapted to be adjusted longitudinally with respect to the gripping members by an abutting spindle $12b$ of a micrometer screw device $12c$ which may be calibrated. The longitudinal position of the support spindle $12a$ for the stone may be locked by a set screw $12d$ entering horizontally in the gripper head. The rotational adjustment of the head may be determined or observed by aid of a scale or index.

The vertically sliding bed 5 , $5a$ is engaged by, or has a depending post $5b$ engaged, by means adapted to bring vertical pressure to bear thereon for the purpose of lifting the stone off the scaife and lowering it into position again as required. These means may comprise a lever 13 pivoted at the forward end of the tang and having one arm extending below the post above referred to, so that the latter rests thereon, while the other extends rearwardly as a manipulating handle which, when depressed, immediately raises the stone off the scaife. The handle may conveniently be in the form of a slotted counterweight 14 longitudinally adjustable on the lever and secured by a screw $14a$.

The vertical slideway of the tang head is practically frictionless so that the stone rests, and is automatically fed downwardly, upon the scaife 15 by gravity as the lapping operation proceeds. The slideway or the mechanical dop may have a vertical rod or other means for attaching a weighting disc or discs in order to vary the pressure with which the diamond engages the scaife, for example the micrometer spindle may have an extension rod $12e$ for receiving a series of weights $12f$ for loading the stone.

The horizontal bed 1 , upon which the slideway block 2 is mounted may be positioned radially of the scaife or at a tangent thereto, or parallel to a radius of or a tangent to the scaife, and the horizontal position of the dop may be roughly effected by locating the slideway block upon the bed and locking it by the T head locking device.

The radial position of the path of the stone upon the scaife may be adjusted to a nicety by the operation of the milled-headed spindle $3a$ carrying the drum driving the tang winding tape. When the chosen radial position of the stone has

been determined the tang is locked by the set screw.

Assuming that the stone has been set up in the gripping fingers $11a$ upon the spindle support 12 in the mechanical dop and the latter placed in position with its lug $6a$ locked by the eccentric spindle $1a$, the raising and lowering lever 13 is manipulated to lower the stone into contact with the scaife when the lapping operation proceeds, the weight $12d$ and the counterweight 14 having been adjusted to afford the desired degree of lapping pressure.

The progress of lapping can be readily observed from time to time by depressing the lever 13 to raise the stone off the scaife and the dop can be immediately released by a turn and withdrawal of the eccentric spindle $1a$. When the stone has been observed the mechanical dop is returned to its position on the vertical bed and relocked in position by reinserting and turning the spindle $1a$ in the barrel lug of the dop.

It will be appreciated that the stone holding head may be adapted to secure stones of a variety of shapes and that heads may be provided which are interchangeable so that a head suitable to a particular stone may be selected and placed in position.

In addition to employing the invention for the usual lapping operation, it may be applied to the grinding of parallel faces upon piezo-electric crystals which require exact and careful treatment.

I claim:

1. A machine of the type indicated having a tang, the axis of which is fixed in a horizontal plane, and a head on the end of the tang adjacent the scaife comprising: a vertical slideway, a slider freely displaceable vertically on said slideway under or against gravity action, a dop or stone mount having a barrel or body provided with a coaxial rotatable member carrying stone holding means, a vertical bed on said slider open to receive said barrel and shaped to locate said barrel laterally with the axis of the rotatable member vertical, complementary interengaging means on the barrel and bed for locating the barrel longitudinally of the bed and releasable clamping means for securing said interengaging means; the arrangement being such that when seated on the bed the barrel and rotatable member are confined to the vertical displacements of the slider.

2. A machine of the type indicated having a tang, the axis of which is fixed in a horizontal plane, and a head on the end of the tang adjacent the scaife comprising: a vertical slideway, a slider freely displaceable vertically on said slideway under or against gravity action, a dop or stone mount having a barrel or body provided with a coaxial rotatable member carrying mechanical stone holding means having gripping fingers and a flat base support for the stone, a vertical bed on said slider open to receive said barrel and shaped to locate said barrel laterally with the axis of the rotatable member vertical, complementary interengaging means on the barrel and bed for locating the barrel longitudinally of the bed and releasable clamping means for securing said interengaging means; the arrangement being such that when seated on the bed the barrel and rotatable member are confined to the vertical displacements of the slider.

3. A machine of the type indicated having a tang, the axis of which is fixed in a horizontal plane radially of the scaife, and a head on the

end of the tang adjacent the scaife comprising: a vertical slideway, a slider freely displaceable vertically on said slideway under or against gravity action, a dop or stone mount having a barrel or body provided with a coaxially rotatable member carrying stone holding means, a vertical bed on said slider open to receive said barrel and shaped to locate said barrel laterally with the axis of the rotatable member vertical, complementary interengaging means on the barrel and bed for locating the barrel longitudinally of the bed, releasable clamping means for securing said interengaging means, and means for rotating the said coaxial member and stone automatically to find the cutting grain of the diamond.

4. A machine as claimed in claim 1 wherein the complementary interengaging means comprise a lug on the barrel adapted to enter a cavity in the bed and formed with a vertical bore, and wherein the clamping means comprise a withdrawable rotatable spindle carrying an eccentric for the lug bore, the arrangement being such that rotation of the eccentric carrying spindle binds the barrel onto the bed.

5. A machine as claimed in claim 1 wherein the slider has a post and a manipulable lever is provided adapted to bear upon the post so that by manipulation of the lever the dop may be quickly raised to place the stone out of contact with the cutting disc.

6. A machine as claimed in claim 1 wherein the slider has a post and a manipulable lever is provided adapted to bear upon the post so that by manipulation of the lever the dop may be quickly raised to place the stone out of contact with the cutting disc and wherein the lever is provided with an adjustable weight for counterweighting the slider and dop to the desired degree and wherein the dop is provided with means for adjustably receiving loading weights.

7. A machine as claimed in claim 1 wherein the tang is mounted in a horizontal slideway, the tang and slideway being of non-circular cross-section to prevent rotation of the tang about its horizontal axis and wherein means are provided for moving the tang axially along its slideway to vary the radial position of the lapping path occupied by the stone on the cutting disc.

8. A machine as claimed in claim 1 wherein mechanical drive means are provided for continually rotating the stone carried by the dop about its vertical axis.

9. A machine as claimed in claim 1 wherein between the adjacent sides of the slider and its slideway, ball races are provided to afford a substantially frictionless displacement of the slider under gravity action.
